UNITED STATES PATENT OFFICE.

FRANK J. BAST, OF NEW YORK, N. Y.

COLLAPSIBLE WARDROBE-RACK.

No. 867,567.

Specification of Letters Patent.

Patented Oct. 8, 1907.

Application filed June 19, 1907. Serial No. 379,679.

To all whom it may concern:

Be it known that I, FRANK J. BAST, a citizen of the United States of America, and a resident of the borough of Brooklyn, city of New York, county of Kings, 5 State of New York, have invented certain new and useful Improvements in Collapsible Wardrobe-Racks, of which the following is a specification.

This invention relates to collapsible wardrobe racks for the support of garments and the object of the invention is to provide a simple and efficient wardrobe rack 10 which admits of expansion in order that garments may be removed and replaced with very little trouble and without injury to the same and which, when collapsed will support a comparatively large number of garments 15 in a confined space.

The detailed construction and the particular features of my invention are set forth in the following specification and pointed out in the claims, while reference is had to the accompanying drawing in which:

20 Figure 1 is a side view of a wardrobe rack embodying my invention. Fig. 2 is a similar view showing the rack expanded. Fig. 3 is a plan view of the collapsed rack. Fig. 4 shows a supporting brace for the rack.

For the purpose of illustration the reference numeral 25 1 indicates the parts of a room or wardrobe on to which the rack is fastened.

2 indicates a rod, which inner end forms a hook 3, and in the instance illustrated the rod is supported by means of the screw eyes 4, 4 and the screw 5. Slidably 30 carried on said rod is a number of toggle links 6, supported by the eye bolts 7 and which carry the double hooks 8 and the single hooks 9, and it will be observed that the outer eye bolt 7, is outside of the outer screw eye 4. When it is desired to remove some of the garments 35 from the rack, the same is pulled out or expanded until the one eye bolt 7 strikes the front screw eye 4 as shown in Fig. 2. In this figure it is clearly seen that

in the expanded position the rack is amply supported by the eyebolts and further, that there is no danger of the toggle links running off the rod as the front screw 40 eye acts as a stop. In this position the garments can easily be inspected and handled without trouble or injurious results, and garments hung on the hook 3 may easily be reached. It should also be noted that by reason of the double hooks 8 being innermost the greatest 45 weight is innermost and there is very little or no sagging of the links.

In Fig. 4 I have illustrated a convenient form of brace for supporting the rack against a wall only.

From the above it will be understood that a large 50 number of garments can be supported by this rack within a narrow space, and at the same time by expanding the rack, easy access to each and every garment is assured, while the operation of the rack is of the simplest.

The form in which this invention is embodied admits of many changes as to size and shape and finish of material and I do not wish to be restricted to the precise form described and illustrated.

What I claim is:

1. A wardrobe rack comprising a laterally supported rod provided with a hook, toggle links provided with hooks adapted to slide on said rod by means of screw eyes, the outer one of which is adapted to leave the rod and means for preventing the inner screw eyes from leaving said rod. 65

2. A wardrobe rack comprising a rod, which inner end forms a hook, screw eyes for laterally supporting said rod adjacent the ends thereof, toggle links slidably carried by said rod, by means of screw eyes, one of which is intermediate the rod supporting screw eyes and hooks carried 70 by said links.

Signed at New York, N. Y., this 17 day of June, 1907.

FRANK J. BAST.
